UNITED STATES PATENT OFFICE.

WILLIAM ROCHE, OF JERSEY CITY, NEW JERSEY.

ELECTRIC CIGAR-LIGHTER.

SPECIFICATION forming part of Letters Patent No. 772,963, dated October 25, 1904.

Application filed January 29, 1904. Serial No. 191,146. (No model.)

To all whom it may concern:

Be it known I, WILLIAM ROCHE, a citizen of the United States, and a resident of Jersey City, Hudson county, New Jersey, have invented 5 certain new and useful Improvements in Electric Cigar-Lighters, of which the following is a specification.

My invention relates to electric cigar-lighters comprising means for producing a spark 10 by which a body of inflammable material, such as alcohol or benzene, is lighted.

The object of my invention is to produce an effective and powerful spark and also to improve the torch by means of which the alcohol 15 is held in proximity to the spark.

Reference is to be had to the accompanying drawings, in which—

Figure 1 is a plan of a cigar-lighter embodying my improvements with parts broken away. 20 Fig. 2 is a sectional elevation on line 2 2 of Fig. 1, and Fig. 3 is a cross-section substantially on line 3 3 of Fig. 2.

A designates a box or casing made of suitable material and containing a battery B, a 25 coil C, and a receptacle D for the fuel E. A wire F connects one terminal of the battery with one terminal of the coil. The other pole of the battery is connected by a wire G with a contact member H, secured at one end, but 30 otherwise free to move elastically. This contact member is made of spring metal and is preferably horizontal. A similar contact member H' is located adjacent to the member H and is connected by a wire I with the second terminal of the coil C. The members H H' may converge toward their free ends, as 35 shown in Fig. 1, and beneath them may be located a drip-pan J. Into the fuel-receptacle D is arranged to dip a torch comprising a handle K, a head or collar L, forming a cover 40 for the said receptacle, a shank M, with a flattened enlargement M', and a coil or spiral wire N, surrounding the enlargement M' and preferably also the adjoining portion of the 45 shank-body. In this manner a sufficiently strong and resistant body is formed for taking fuel from the receptacle D and passing

it over the contact members H H'. Fig. 3 clearly shows the relatively large capacity of the holder thus produced and also that the 50 enlargement M', being located within the coil N, forms a brace or stiffener for the coil.

When the torch is applied to the contact members H H' with its coil N, the said members are bent toward the drip-pan J, as indicated by dotted lines in Fig. 2, and the circuit through the battery, the coil C, and the members H H' is closed through the torch-wire N. As soon as this wire passes beyond the ends of the members H H' these members being released will by their elasticity 60 snap upward, their quick movement producing a powerful break-spark. This spark ignites the fuel carried by the torch, and the latter may then be used for lighting cigars or 65 for analogous purposes.

Various modifications may be made without departing from the nature of my invention.

I claim and desire to secure by Letters Patent—

1. A device of the class described, comprising two conducting members extending alongside of each other, said members being stationary at one end and elastically flexible in the same direction at their other ends, a 75 spark-producing device connected with the stationary ends of said members, a drip-pan located beneath the flexible ends of said members, and a conducting fuel-bearing torch adapted to move said members in the same 80 direction toward the drip-pan against their elasticity and to then release them for a quick break of the circuit.

2. A device of the character described, comprising two converging conducting members 85 extending alongside of each other, said members being secured at one end and elastically flexible in the same direction at the other convergent ends, a spark-producing device connected with said members, and a conducting fuel-bearing torch adapted to move said members against their elasticity and to then release them for a quick break of the circuit. 90

3. In a device of the character described,

contact members, a spark-producing device connected therewith, and a fuel-bearing torch adapted to engage said members, said torch comprising a shank having a flattened portion, 5 and a fuel-holding coil surrounding said flattened portion.

In testimony whereof I have signed my name

to this specification in the presence of two subscribing witnesses.

WILLIAM ROCHE.
